UNITED STATES PATENT OFFICE.

LOUIS ZWEIG, OF BROOKLYN, NEW YORK, ASSIGNOR TO SUN RISE LAMP MFG. CO. INC.,
A CORPORATION OF NEW YORK.

DESIGN FOR A TABLE TORCHÈRE OR ANALOGOUS ARTICLE.

Application filed October 19, 1927. Serial No. 23,802. Term of patent 3½ years.

To all whom it may concern:

Be it known that I, LOUIS ZWEIG, a citizen of the Republic of Austria, and a resident of the city of Brooklyn, county of Kings, and State of New York, have invented a new, original, and ornamental Design for a Table Torchère or Analogous Article, of which the following is a specification, reference being had to the accompanying drawing, forming a part thereof.

In these drawings:

Figure 1 is an elevational view of the table torchère or analogous article; and

Figure 2 is a diagrammatic edge view of the same taken at right angles to the plane of Figure 1.

The dominant feature of the design consists in the employment of a base A having the representation of a ship which is surmounted by a torchère having a glass cylinder B adapted to inclose a light source.

I claim:

The ornamental design for a table torchère or analogous article substantially as shown and described.

LOUIS ZWEIG.
